UNITED STATES PATENT OFFICE.

WILFORD J. HAWKINS, OF THE UNITED STATES ARMY.

GUN-SIGHT.

No. 861,652.

Specification of Letters Patent.

Patented July 30, 1907.

Application filed December 7, 1906. Serial No. 346,808.

To all whom it may concern:

Be it known that WILFORD J. HAWKINS, a lieutenant in the army of the United States, and a citizen of the United States, residing at Springfield, in the 5 county of Hampden and State of Massachusetts, has invented certain new and useful Improvements in Gun-Sights, of which the following is a specification.

This invention relates to new and useful improvements in gun sights and it particularly pertains to a 10 novel sight for shoulder arms.

The invention specifically comprises a gun sight comprising a fixed base, a movable base, a sight leaf carried upon said movable base and a slide block movable longitudinally of said sight leaf. These elements 15 constitute the rear sight and are employed in connection with a novel embodiment of front sight.

The invention aims as a further object to provide novel means for adjusting the sight leaf by means of a windage scale to compensate the flight of the bullet in 20 accordance with the direction and strength of the wind.

The invention aims as a further object to provide a slide block embodying means for locking the same against play in any position upon the sight leaf which said slide block may be adjustably moved.

25 The invention aims as a further object to provide a sight in which is embodied an apertured sight disk or plate having an adjustment independent of the slide block, in order that the sight disk or plate may be set at any desired adjustment without moving the 30 slide block. Consequently a marked advantage is attained over the prior art wherein the slide block and sight plate are moved synchronously when it is desired to adjust the latter so as to bring a selected opening into the line of vision.

35 A still further object of the invention is to provide in connection with the means for moving the slide block vertically of the sight leaf, novel means for indicating the degree of such movement and from which sighting calculations may be made. In specific terms 40 the means for moving the slide block comprises an elevating screw having its threads at a selected pitch whereby the slide block is moved by one complete or fractional revolution of said screw, a corresponding distance which is a known and determinate fraction of 45 the sight radius.

The invention aims finally to provide a sighting mechanism in which the mechanism for adjusting the bases with relation to the windage scales is completely 50 housed and consequently protected from dust and rain.

55 The detailed construction will appear in the course of the following description in which reference is had to the accompanying drawings forming a part of this specification, like characters of reference designating similar parts throughout the several views, wherein,

Figure 1 is a front elevation of a gun sight constructed in accordance with my invention. Fig. 2 is a side

elevation thereof. Fig. 3 is a top plan view of a fixed base. Fig. 4 is a section on the line 4-4 of Fig. 2. Figs. 5 and 6 are respectively front and rear plan views of elements of the slide block to be hereinafter specifically referred to. Fig. 7 is a fragmentary side elevation of the slide block in position upon the sight leaf. Fig. 8 is a horizontal section of the sight disk and its associated parts which are carried by the slide block. Fig. 9 is a top plan view of means for engaging the 65 slide block with its adjusting mechanism. Fig. 10 is a front elevation of the slide block. Fig. 11 represents the drift slide plate which moves along the sight leaf in front and top elevation. Fig. 12 is a top plan view of the sight leaf. Fig. 13 is a section on the line 13-13 70 of Fig. 4. Figs. 14, 15 and 16 are respectively rear, front and side elevations of the front sight, and Figs. 17 and 18 are diagrams which will be specifically referred to hereinafter in describing the mode of use of certain elements.

Referring specifically to the accompanying drawings the numeral 1 designates the barrel of a gun which adjacent to its stock is provided with a fixed base 2 in the form of a sleeve surrounding said barrel, and upon which the elements of the sight are mounted. The 80 base 2 is provided at a point off-center adjacent its forward end with an enlarged vertical post 3 which serves as a pivot for the movable base 4. The base 2 adjacent its forward end is formed with a slightly curved transverse slot 5 through which projects a depending post 6 85 carried by the base 4. The post 6 is provided with a threaded aperture in its lower end through which is received an adjusting screw 7 transversely journaled in the side walls of the base 2, the screw 7 carrying at one end thereof a knurled finger piece 8 and being surrounded within the base 2 by an expansive coil spring 9 for taking up the back lash or play of the screw 7 in the fixed base 2 and of the post 6 with relation to said screw. As shown in Fig. 13 the screw 7 is capable of a limited play by reason of the openings 10 in the base 2 95 through which said screw projects, being of slightly enlarged diameter. This play is necessary in order to compensate for the amplitude of the pivotal motion of said base 4 and the said post 6 carried thereby. It will be apparent that the base 2 serves as a housing for the 100 traversing mechanism to protect the same from dust and rain.

The fixed base 2 is provided at each end thereof with windage scales 11 and 12 arranged at a slight incline so as to present their surfaces at the proper angle to the 105 eye of the marksman with the piece at the shoulder. In this relation the scales 11 and 12 overlie the correspondingly inclined ends of the base 4. The windage scales 11 and 12 are each graduated in accordance with different and respective bases of computation by means 110 of which the marksman sets his sight to correct for the strength and direction of the wind.

In the following illustrations reference is had to the chart shown in Fig. 17 in which O represents a point on the line of fire towards which the various winds blow and which for the purposes of illustration is centrally located in the circle. The Roman numerals I to XII represent equi-distant points in alinement with O by which the direction of the wind is determined. To illustrate the manner of using the scales 11 and 12, we will refer to the scale 11 on the rear end of the base 4, 5 which is arbitrarily so graduated that each smallest division or calibration corrects for what is known in the parlance of marksman as a "two mile an hour, three o'clock wind", that is a wind which blows from the right at a right angle to the line of fire with a velocity of 10 two miles an hour. As shown in Fig. 17 such a wind will blow from III to O. Now, with such a basis of calculation in mind, it will be readily apparent that a four mile an hour one o'clock wind has the same deflecting power as a two mile an hour three o'clock wind, 15 the last wind being along the line I—O and forming an angle of 60° with the line III O. This will be understood since the cosine of 60° is one half. If in practice, the marksman faces a two mile an hour one o'clock wind he calculates therefor by multiplying 20 I—O representing the deflecting strength of a two mile an hour 1 o'clock wind by the cosine of the angle I O III or one half. By such multiplication we find that the deflecting power of a two mile an hour one o'clock wind is equal to $\frac{1}{2}$ of O—III which represents the deflecting power of a two mile an hour three o'clock wind, 25 or O—P. Other calculations with different angles from the line O—III as a leg are made accordingly. Therefore for a two mile an hour one o'clock wind the movable base is accordingly set half a space or division 30 with relation to the proper calibration.

To the rear of the base 4 a sight leaf 13 of open rectangular shape is pivoted. The sight leaf 13 has its vertical sides marked with indexed calibrations 14 which indicate the respective sight settings for the 40 various ranges under normal conditions of atmosphere. The base 4 is recessed to receive the sight leaf therein in its folded position and said sight leaf is held in either its folded or raised position by means of a strong leaf spring 15 which bears against that portion of the sight 45 leaf embodied in the pivot joint 16.

In Fig. 10 is shown a preferred form of slide block employed in connection with the sight leaf 13. This slide block is designated by the numeral 17 and is provided at each side thereof with vertical ways 18 which 50 receive the vertical sides 14 of the sight leaf 13, and are of greater width than said sides so as to have "play" with relation thereto for a purpose to be described. The slide block 17 is closed by an ornamental cap plate 19 illustrated in Fig. 5 which is rigidly fixed thereto and in its lower portion is provided with a central opening 20 which registers with a semi-circular recess 21 in the lower portion of the slide block 17. The cap plate 19 is secured to the slide block by nuts or screws passing through corresponding openings 22 in 60 said cap plate and slide block. The means for vertically adjusting the slide block to any desired position on the sight leaf comprises a vertical screw 23 journaled in the upper and lower portions of the sight leaf and in parallelism with the perpendicular axis thereof. 65 The screw 23 at its upper end carries a notched thumb

nut 24 provided with marked reading adjacent each notch to indicate the degree of rotation or partial rotation of the screw 23. There are preferably ten of such readings which divide a single revolution of the screw 23 into ten equal parts. The sight leaf 13 is provided with an index line 25 which points to the calibrations on the nut 24.

The screw 23 has its threads so pitched that each rotation thereof moves the slide block 17 a predetermined and known distance upon the sight leaf 13. 70 Hence by referring to the scale on the nut 24 the marksman knows as he rotates the screw 23 to just what degree the slide block 17 is moved upon said sight leaf. The advantage of this arrangement will be apparent from the following illustrations based on the diagram shown in Fig. 18. In these illustrations it is assumed for the sake of example that the threads on the screw 23 are so pitched that one revolution of said screw moves the slide block vertically by an amount equal to $\frac{1}{6}$ of the sight radius. In the following 80 equations B C represents the sight radius, B A the sight setting, C D the range and D E the distance subtended at the target by the sight setting. From the principle of similar triangles we have A B : B C :: E D : D C. With the pitch of the thread as above stated, it 85 will be evident that the movement of the slide block due to one revolution of the elevating screw will at the target correspond to a vertical movement equal to $\frac{1}{6}$ of the range or C D, on account of the principle of similar triangles. With the fraction $\frac{1}{6}$, which is chosen 90 simply for convenience of illustration, the subtended vertical movement at the target at a range of 1,000 yards (equal to 36,000 inches) by one revolution of the adjusting screw is $\frac{1}{6} \times 36,000$ or 40 inches. Hence each division on the nut 24 at a range of 1,000 yards 100 represents a subtended vertical movement at the target of $\frac{1}{6} \times 40$ inches or 4 inches. Therefore at a range of 500 yards one revolution of the elevating screw corresponds to $\frac{5}{6} \times 40$ or 20 inches which is subtended at the target and each division of the thumb nut corresponds to $\frac{1}{6} \times 20$ inches or 2 inches, etc. From these illustrations, the principle of the elevating screw 23 will be apparent, *i. e.* that its pitch is so selected as to cause the slide block to be raised or lowered by one revolution of the elevating screw by an amount equal 110 to some convenient fraction of the sight radius B C. The slide block 17 is provided with a horizontal recess 26 extending from one side thereof to a point near the center and having received therin a sliding member 27. The latter is in turn recessed as at 28 to intersect 115 the side of the sight leaf 13 and at its inner end is formed with a semi-circular threaded recess 29 which bears against and meshes with the threads of the screw 23.

For the purpose of maintaining the member 27 in engagement with the screw 23, an expansive coil spring 30 is seated in said member and bears against a projecting web 30^a provided in the recess 26 adjacent to its outer end. The member 27 may be moved manually to disengage the same from the screw 23 and is accordingly formed with a milled or knurled end 31. In Fig. 9 the view of said member is on an enlarged scale.

The sight leaf 13 has the inner edges of its side bars inclined in parallelism as at 32 so as to afford an under-cut recess 33 having its axis extending at an angle 130

to the perpendicular axis of said sight leaf. The slide block 17 in its vertical adjustable movement follows the axis of the under-cut recess 33. This is possible on account of the "play" above referred to between 5 the recess 18 and the side bars of said sight leaf. For the purpose of guiding the slide block in the under-cut recess 33, a slide plate 34 to be called the "drift" slide plate is provided. The recess 33 is of dovetail shape and the plate 34 conformably fits therein. The 10 plate 34 is illustrated in detail in Fig. 11 and is formed with openings 35 through which pass fastening means to screw said plate to the cap plate 19 and with an enlarged opening 36 which registers with the opening 20 and the recess 21. Through the uppermost of the 15 openings 35 of said cap plate, a pin 37 is projected. This pin 37, while serving the incidental function of a fastening means for the drift slide plate also serves to carry at its front end a sight disk 38. The disk 38 is formed with openings 39 of various sizes and shapes 20 in accordance with the character of the mark, the personal preference of the marksman and the conditions of light. In adjusting the disk 38 so as to bring a desired opening 39 in registry with the openings 36, 25 20 and 21, said disk is manually rotated, the rotation thereof being facilitated by the presence of a knurled 30 edge 40. For the purpose of holding the disk 40 at any position to which it may be set, ratchet projections 41 are provided centrally upon the rear face thereof and engage in corresponding notches 42 pro- 35 vided upon the front face of the slide block cap 19 as is clearly shown in Figs. 5 and 6. The projections 41 are held in engagement with the notches 42 by means of a spring 43 surrounding the pin 37 and interposed between the rear face of the slide plate 34 and the en- 40 larged head 44 of said pin. In Fig. 8 I have illus- 45 trated the disposition of the various elements, the cap plate 19 being next to the sight disk 38 and the plate 34 being interposed between said cap plate and the slide block 17, the latter being omitted from Fig. 8. It will of course be understood that the cap plate 19 is of a size and shape to completely cover all of the 50 openings 39 in the plate 38 except the opening which is aligned with the openings 36 and 20 and the recess 31. In Figs. 14, 15 and 16 I have illustrated a novel 55 embodiment of front sight comprising a sleeve 45 fixed to the barrel and having a rearwardly and downwardly inclined upper surface 46 having a central longitudinal dovetail groove 47 therein. Slidably mounted in the groove 47 is a block 48 having a dove- 60 tailed projection on its inclined lower face which interfits said curve. The block 48 is formed in its upper face with a transverse dovetailed groove 50 within which is received a transverse dovetailed projection 51 carried upon the sight 52. It will hence be ob- 65 served that a vertical and lateral adjustment of the sight 52 is permissible through the connections de- 70 scribed between the same and block 48 and between the block 48 and the fixed base 45. The manner of use will be readily apparent. The 75 front and rear windage scales 12 and 11 are arbitrarily

calibrated in order that the base 4 may be set to correspond to the velocity and direction of the wind by using one or the other of said scales. The back apertures 39 which the marksman uses depends upon the personal preference of the marksman, the clearness 65 of the mark and the atmosphere. When the base 4 has been set with relation to the proper windage scale 11 or 12, by means of the threaded shaft 7, the slide block 17 is moved to raise the sight disk to the proper elevation. The scale on the nut 24 aids materially in 70 this adjustment. When it is desired to raise the slide block quickly without the use of the screw, the member 27 is pushed inwardly against the tension of the spring 30 and the recess 29 is disengaged from said screw. The slide block may then be moved manu- 75 ally in either direction upon the sight leaf. The under-cut groove 33 is extended to the left since in shoulder arms the twist of the rifle is to the right and hence the drift of the bullet is to the right of the line of fire. Hence the drift groove 33 is inclined to the 80 left so as to automatically correct for a right hand drift. In those cases where the twist of the rifle is to the left, the drift groove 33 will of course extend to the right as will be readily understood.

While the elements herein shown and described are 85 well adapted to serve the functions set forth, it is ob- 90 vious that various minor changes may be made in the proportions, shape and arrangement of the several parts without departing from the spirit and scope of the invention as defined in the appended claims. 90

Having fully described my invention I claim:

1. A device of the type set forth comprising a fixed base including a tubular portion adapted to surround the barrel of a gun, a movable base pivoted thereto, a transverse threaded shaft having lateral play in said fixed base, said fixed base having in its upper surface a transverse curved slot, a post depending from said movable base passing through said slot and having a threaded opening surrounding said shaft in engaged relation and sighting mechanism carried by said movable base. 95

2. A device of the type set forth comprising a fixed base including a tubular portion adapted to surround the barrel of a gun, a movable base pivoted thereto, a transverse threaded shaft having lateral play in said fixed base, said fixed base having in its upper surface a transverse curved slot, a post depending from said movable base passing through said slot and having a threaded opening surrounding said shaft in engaged relation, a sight leaf pivotally mounted at one end of said movable base and a leaf spring carried by said movable member and arranged to hold said sight leaf. 100

3. A device of the type set forth comprising a fixed base, a movable base pivoted thereto, a transverse threaded shaft having lateral play in said fixed base, said fixed base having in its upper surface a transverse curved slot, a post depending from said movable base passing through said slot and having a threaded opening surrounding said shaft in engaged relation and sighting mechanism carried by said movable base. 115

In testimony whereof I affix my signature in presence 120 of two witnesses.

WILFORD J. HAWKINS.
